UNITED STATES PATENT OFFICE.

GUSTAV EGLOFF AND HARRY P. BENNER, OF CHICAGO, ILLINOIS, ASSIGNEES TO UNIVERSAL OIL PRODUCTS COMPANY, OF CHICAGO, ILLINOIS, A CORPORATION OF SOUTH DAKOTA.

APPARATUS FOR TREATING EMULSIFIED OIL.

Application filed October 21, 1920, Serial No. 418,566. Renewed March 24, 1927.

This invention relates to apparatus for treating emulsified oil and refers more particularly to the dehydration of emulsified petroleum oils such as California or Mexican crude petroleums, bottom settlings or the like.

The object of the invention is to cause the breaking down of the emulsion by mechanical means and more specifically by causing the oil to pass through a series of small orifices under a predetermined pressure. The oil may be treated cold, although as a modification of the invention, the oil may be heated if desired, to any given temperature short of vaporization.

In the drawings:

Fig. 1 is a vertical view of the treating chamber and associate piston and valve mechanism.

Fig. 2 is a cross sectional view taken on lines A—A of Fig. 1.

Fig. 3 is a cross sectional view taken on lines B—B of Fig. 1.

Fig. 5 and Fig. 4 are end and side views respectively of the ball valves.

Fig. 6 is a plan view showing the driving mechanism. Fig. 7 is an end view of the same.

Fig. 8 is a detail view of certain guides of the driving mechanism.

Referring in detail to the drawings, 1 designates as a whole the treating chamber, provided with an inlet suction pipe 2, leading to the valve chamber 2^a. 3 designates the spring valve members and 4 the suction chamber. In the main chamber 1 is mounted a piston 5, having piston rod 5' extending out through stuffing box 5''. This piston is provided with a series of spaced, circumferentially extending ducts 6, which are small orifices of predetermined size and open at either end. At the rear end of the piston head, these ducts are controlled by the ball valves 7 mounted in the valve chambers 45 or valve caps 7'. The arrangement is such that as the piston travels forward, the ball valves are unseated and the emulsified oil forced under pressure through the ducts 6. As the piston returns, the ball valves are closed and the oil in which the emulsion has now been broken down, forced out into the discharge chamber 8 and thence through the valves 9 where the oil and water will separate by gravity.

As the piston moves on its return stroke, 55 it forms a suction at the front end of the cylinder and emulsified oil is drawn in through the valves 3. It will thus be seen that the piston simultaneously draws in emulsified oil on one side of the piston and 60 discharges the de-emulsified oil on the other side of the piston. On the forward stroke of the piston, the oil already in the front end of the treating chamber or cylinder is forced under pressure through the orifices 6 and as 65 the oil is forced to pass through these very fine openings, the emulsion will be broken down. The size of the openings will depend upon the degree of emulsification; with oils that are very badly emulsified and in which 70 it is difficult to break the emulsion, very fine ducts may be necessary. It is also to be understood that the number of these ducts may be multiplied.

Referring now more particularly to Figs. 75 6 and 7, there is there shown the manner of reciprocating the piston. The piston rod is provided with an extension 5^a and the stroke of this piston rod or piston can be shortened or lengthened by means of the 80 device 11, which can be moved along and set at any desired position on the rod 12. On the piston rod is fixedly secured a crosshead 13, which is adapted to strike the pins 11 upon the reciprocation of the extension 5^a. 85 The crosshead as it strikes the pins 11 actuates the pivoted member 14, which is secured to the rod 12. This pivot member in turn is arranged to shift the belts 15 and 16, so as to reverse the direction of movement of 90 the piston as will hereinafter more clearly appear. In the drawing, the belt 15 is running on the loose shaft 17. When the cross head comes in contact with the pins 11, the belt is shifted over to the pulley 18, which 95 starts the mechanism operating in the opposite direction. At the end of the shaft 17 is a pinion gear 19, which engages with the rack cup on the under side of the piston rod extension 5^a, thus serving to give a back and forth actuation to the piston member. The pulley is driven by means of the motor 20. It will be appreciated that the two outer pulleys on the shaft 17 are idlers and that the belts are shifted alternately to the fixed pulley, so as to properly reciprocate the piston. The cross head 13 moves in the rectangular guide frame 21 as shown clearly in the draw-

ings. The manner of actuating the driving mechanism should be apparent from the foregoing description and need not be described in detail.

5 We claim as our invention:

An apparatus for de-emulsifying hydro-carbon oils, comprising a cylinder having a valve controlled oil inlet and a valve controlled outlet, a movable piston adapted to 10 reciprocate in said cylinder intermediate

said inlet and outlet, a plurality of restricted passageways, extending through said piston, means for reciprocating the piston under pressure to force emulsified oil through said passageways, means for preventing the return of such oil through said passageways when the piston is reciprocated to eject the de-emulsified oil. 15
